UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

DESIGN FOR A DISPLAY-CABINET.

53,680.

Specification for Design.

Patented Aug. 5, 1919.

Application filed April 4, 1919. Serial No. 287,622. Term of patent 14 years.

To all whom it may concern:

Be it known that I, JOHN L. FLANNERY, Jr., a citizen of the United States, residing at Chicago, county of Cook, and State of Illinois, have invented a new, original, and ornamental Design for a Display-Cabinet, of which the following is a specification, reference being had to the accompanying drawing, forming a part hereof, in which—

The figure represents a perspective view of a display cabinet in accordance with the design.

I claim:

The ornamental design for a display cabinet, as shown.

JOHN L. FLANNERY, JR.
